S. S. Cowell

UNITED STATES PATENT OFFICE.

SELDEN S. COWELL, OF HUNTSDALE, PENNSYLVANIA.

COLLAPSIBLE FUNNEL.

1,408,865.

Specification of Letters Patent. Patented Mar. 7, 1922.

Application filed July 13, 1921. Serial No. 484,332.

To all whom it may concern:

Be it known that I, SELDEN S. COWELL, a citizen of the United States, residing at Huntsdale, in the county of Cumberland and 5 State of Pennsylvania, have invented certain new and useful Improvements in a Collapsible Funnel, of which the following is a specification.

This invention relates to funnels and more 10 particularly to a collapsible funnel adapted to be arranged in the radiator opening of an automobile whereby water may be poured into the radiator when the funnel is opened.

One of the objects of the invention is to 15 provide a collapsible funnel of this character which will fit at all times in the radiator and be arranged in a manner that will permit it to be opened and disposed above the radiator opening when the funnel is to be used.

20 Other objects of the invention will appear upon consideration of the following detail description and accompanying drawings, wherein:—

Figure 1 is a perspective view of the funnel constructed in accordance with my invention,

Figure 2 is a longitudinal section through the funnel tube showing the funnel folded or collapsed within the tube, and

30 Figure 3 is a fragmentary perspective view of a portion of the funnel showing the interior construction thereof.

Referring to the drawing by numerals, the cylindrical tube 1 may be of any desired 35 length and has its lower open end 2 slightly turned inwardly to form an annular flange 3. The upper or opposite end of the tube may be flared outwardly if desired and the tube is intended to be fitted in the opening of 40 the radiator of an automobile and held in position therein in any desired manner.

The collapsible body of the funnel includes a cylindrical sleeve 4 to which a plurality of spring arms 5 are attached. Each 45 spring includes an attaching finger 6 which is fastened to the sleeve 4 and a coil spring 7 from which projects the elongated spring arm 8. Any number of these spring members may be arranged around the sleeve 4 50 and they support the flexible funnel body 9 which consists of canvas or any other suit-

able material which may be folded in the manner shown in Fig. 2. The springs 7 act to normally extend the spring arms outwardly at an angle. The lower end of the cloth body 9 of the funnel is secured to the sleeve in any preferred manner in the present instance the fastening being indicated by a binding wire 10. The upper marginal edge of the funnel body is provided with a marginal hem 11 to which is fastened the upper end of the spring arm 8. When the funnel is not in use, the same will be thrust downwardly in the tubular member 1 as shown in Fig. 2 until the sleeve member 4 60 engages the annular flange 3, the cloth body of the funnel folding into the tube as shown in Fig. 2, whereupon the usual radiator cap may be mounted in position on the radiator thus covering the upper end of the folded 65 funnel. When the funnel is to be used, the radiator cap will be removed and the funnel drawn upwardly out of the tube 1 whereupon the springs will automatically act to throw the spring arms 8 outwardly so that 70 the funnel will form the arrangement shown in Fig. 1 of the drawing and permit the operator to pour water into the funnel so that it will be conducted into the radiator.

Minor changes may be made in the details 80 of construction without departing from the spirit of the invention or the scope of the claim hereunto appended.

What is claimed is:—

A collapsible funnel comprising an elongated tube, a sleeve slideable in the tube, a flexible funnel body of cloth material having its tapered end connected with said sleeve, and spring ribs secured to and extending the length of said funnel body having their 90 lower terminals secured between the sleeve and the cloth of the body, said ribs having coil springs adjacent the jointure of the funnel body with said sleeve, whereby the former will be moved to a flared or open 95 position when withdrawn from said tube.

In testimony whereof, I have affixed my signature in the presence of two witnesses.

SELDEN S. COWELL.
